UNITED STATES PATENT OFFICE.

JOHN C. MENDONCA, OF NEW BEDFORD, MASSACHUSETTS.

SAFETY DEVICE.

Application filed December 31, 1926. Serial No. 158,380.

The invention has for an object to provide a device adapted to be readily installed on engines of various types for use to positively prevent accidental operation of the engine from any cause whatever, such as a leaky throttle, casual opening of the throttle, loosening of the brakes while the engine or train is on a grade, or other causes tending to cause the train to move alone. It is a further important purpose to provide such a device which will be applicable to use in emergency as a train stopping means. In this connection it is an aim to give a desirable mechanism whereby the action of the device will be synchronized with the engine action whereby positive operation is assured regardless of the position of the engine parts when a controlling device is operated. This particular embodiment of the invention aims to present a chock or locking member movable to be interposed between the cross head of the piston rod, and the adjacent cylinder-head or adjacent framing, with means cooperative with the cross head at will to cause locking of the engine mechanism.

It is an important aim to enable the operation or control of the device with a minimum of physical effort and in an extremely simple manner.

A further purpose is to enable the construction of such a device in a very compact form, so that it may be accommodated to space already available, without modification of customary engine construction, and without projections extending to an undue distance laterally.

Additional objects, advantages and features of invention will appear from the construction, combination and arrangement of parts hereinafter set forth and shown in the drawings, in which

Figure 1 is a side elevation of an engine equipped with my invention.

Figure 2 is a top view thereof.

Figure 3 is an enlarged detail view of the cross-head guide and adjacent parts, including the locking mechanism, with resetting parts removed.

Figure 4 is a top view of the parts in Figure 3.

Figure 5 is a cross section centrally of Figure 3 looking forward.

Figure 6 is a detail of a latch lifter.

Figure 7 is a side view showing the mechanism in position.

Figure 8 is a cross section centrally of Figure 7.

Figure 9 is a detail of the detent.

There is illustrated an engine 10 of a standard type now in use, including a cylinder head 11, cross head guide 12, piston rod 13, cross head 14 connected thereto and operable in the guide 12, and the connecting rod 15 pivoted in the cross head, these elements being of the customary construction.

The cross head guides are supported by the usual guide yoke 16. Slidably engaged with the respective guide bars of the cross head guide there are upper and lower sliding blocks 17 and 18, the latter carrying three horizontal laterally projected guide bolts—a middle one 19 and two end ones 20. The upper block 17 has a single horizontal bolt 21, similar to and aligned vertically with and over the one 19. A frame piece 22 is in the form of an inverted T-apertured at each end of its stem and at the outer ends of the arms. It is supported slidably by the bolts

named which are engaged in respective apertures mentioned, as shown. Around the bolts 19 and 21 there are engaged helical springs 23 confined between the frame piece 22 and the heads of the bolts, by which the frame piece is pressed forcibly inwardly

against the blocks 17 and 18. Two horizontal arms 24 are formed on the inner side of the stem of the frame piece 22, one above and the other below the piston rod, and projecting beyond a vertical plane coincident with the axis of the rod. Carried by each of these arms there are two horizontal shafts 25, parallel to the piston rod and on opposite sides thereof, around the ends of each of

which there are helical springs 26 bearing outwardly against the blocks 27, slidably mounted on the ends of the shafts. There are four of these blocks 27, of oblong shape, horizontally disposed above and below the piston rod, two adjacent the cylinder head and two next the cross head. Each is bored adjacent each end to receive slidably the ends of the two shafts thereadjacent, each bore being slotted at opposite sides for a distance from its outer end to receive slidably a pin 28 engaged transversely through the respective shaft to limit outward movement of the block under pressure of the

springs. The blocks 27 adjacent the cylinder head are shaped to conform to the shape of the space within the cross head guide at the end, including the supporting lugs 29 for the cross head guide, and the packing box 30 around the piston rod, so that an ample area of bearing will be provided for the action to be described. The blocks 27 adjacent the cross head are formed 10 to seat snugly thereagainst at the same time.

The length of the bolts 19—20—21 is such as to permit the outward movement of the piece 22 until the blocks 27 clear the path of the cross head, and it is normally so held 15 against the action of the springs 23 by a detent yoke 31, including a centrally pivoted lever portion 32 carried by a suitable extension of the block 17. The yoke fits snugly around the bolt, bearing both against the 20 block 17 and the frame piece 22. The lever portion includes an operating arm 33 extending rearwardly, and arranged to be engaged and depressed by a rocker arm 34 when moved forwardly, for lifting of the 25 yoke and inward movement of the piece 22 under action of the springs 23. The yoke proper and the arm 33 may be fixed on opposite ends of a shaft 35 revolvably mounted on the block 17, as shown. The rocker arm 30 is similarly mounted on the inner end of a shaft 36 also revolvably mounted on the block 17, the outer end of which has fixed thereon a similar arm 37 extending downwardly and engaged by a contractile spring 38 attached 35 to the bracket plate 16, and tending to draw the arm rearwardly. The arms 34 and 37 are held against this movement normally by means of a detent device 39 mounted on the yoke 16 and adapted to engage and hold the 40 arm 34 at the rearmost limit of its movement, and being releasable by a link 40, bell crank 41, rod 42 and connected lever 43 in the engine cab 44, as will be described. A latch bill 45 is mounted pivotally on the 45 shaft 36, adapted when lowered to engage over the upper edge of the plate 16 and hold the blocks 17 and 18 against sliding movement on the cross head guides. On the shaft 36 there is fixed a shouldered collar 46, the 50 shoulder 46' of which is arranged so as to strike the latch at a certain point in the forward movement of the arm 34 and lift the latch. The arm 37 is of sufficient radius and spaced outwardly of the guide bars 12 55 enough to engage a striker block 47 on the outer side of the cross head, this block being inclined at its rear part as at 48. The spring 38 is connected to a lug 50 on the side of the arm 37, whereby when the detent 39 60 is released the arm 37 will be drawn rearwardly to the position shown in Figure 7. This arm is of such length as to swing into the path of the block 47, and tends to remain in this path so that rearward movement 65 of the block 47 will swing the arm 37 with

it, the inclined face 48 fending the arm upwardly until the block may pass thereunder. The block is of a length to clear the arm entirely in its rearward movement until the return of the crosshead under resetting of 70 the device as will be described. The movement of the arm 37 rotates the shaft 36, and causes the arm 34 to bear downwardly on the arm 33 of the member 31 and permits inward movement of the frame piece 22 so that 75 forward movement of the crosshead is checked. By means of a suitable spring 53 the members 17 and 18 are held at the rear limit of their movement, so that upon the rotation of the shaft 36 to initial position, the latch 45 will engage over the bracket plate 16 holding the parts against loose movement on the crosshead guide. The detent 39 comprises a lug 54 on the yoke 16, having a crank dog 55 pivoted thereon, the pivot axis being within the radius of the arm 34. The dog has an eccentric block 57 projecting across the path of the arm 34, and borne into the path of the arm by a spring 58 seated against the bracket 16, a check lug 59 being 80 formed on the lug 54 to limit the movement of the dog by the spring. The dog has also a crank arm and wrist 60, the latter being engaged in the slotted end of a link 40, the upper end of which is connected to an outwardly projecting arm on the rod 42 connected thereto, the latter being extended into the engine cab 44 and connected to a suitable 85 operating lever 43.

For resetting the device there is pivoted 90 on the block 17 a bifurcated lever yoke 61 carried by suitable bracket arms 62 on the block 17, the extremities of the furcations carrying revolvably a short shaft 63 engaged through the stem of the frame piece 22. 105 The yoke is provided with a stem 64 extending upward and inclined inward slightly when the device is in released position, and carried on the rod 42 there is an arm 68 at the forward end of which there is fixed 110 the elongated crank pin or stub shaft 69 movable in an arc of such radius that it will strike the arm 64 when the blocks 17 and 18 are at either limit of their movement, thus moving the frame piece 22 outwardly and 115 removing the impediment from the path of the piston cross head. It is only necessary for the engineer to move the lever 43 to initial position while he opens the throttle and moves the piston to the forward limit 120 of its movement. In order to permit operation of the lever 43 it may be necessary first to move the crosshead to rearmost position, depending upon the circumstances attending the release of the device previously.

In use, the device may be used as a safety appliance on standing engines to prevent 125 casual operation of the train, and it should be a requirement that the device is to be released whenever a terminal is reached, or

when a stop of more than a predetermined duration is to be made, and whenever the engineer leaves the cab. The device may be released quietly by use of the lever 61 when 5 the cross head is at rearmost position.

In case of emergency it is only necessary to move the lever 43 to operate the detent, and the blocking action will not occur until the crosshead is in proper position for efficient operation of the device. The lever 43 should be arranged so that it will remain in released position, and if desired any suitable means may be provided whereby it will tend to move to released position and 10 will be held in set position by a detent, the release of which will cause automatic operation of the device.

In emergency action, or whenever the engine tends to move when the device is in released position, if the crosshead is at an intermediate or forward position, as soon as the detent 39 is operated, the spring moves the arm 34 forwardly until near or against the arm 33, but without sufficient force to 25 lift the detent yoke 31. The arm 37 has then fallen into the path of the block 47, and the rearward movement of the block will move the arm 34 with sufficient force to lift the yoke 31 just after the cross head has 30 cleared the path of the blocks 27 when moved inwardly. The connecting rods are then on dead center at the respective sides of the engine, and the springs 26 and 53 will allow the cross head to move forwardly approximately half a stroke under sufficient pressure, the frame piece 22 and blocks 17 and 18 being carried therewith part way. The cross head will be checked at a point where 35 resistance to the rotation of the drivers of the engine may be exerted with the maximum efficiency, the resilient action of the springs 26 serving to reduce the shock and minimizing the liability of fracture of the main rod 15.

45 I claim:

1. In a locomotive, the combination of a reciprocating power member, a fixed element, a member movable into the path of the reciprocating member between said reciprocating member and the fixed element, means to move the movable member, and means to hold the movable member in inoperative position at times.

50 2. In a locomotive, the combination of a crosshead guide and cross head and supporting means therefor, a blocking device movably mounted on the supporting means for engagement in the path of the cross head at times, means tending to move the blocking device into engaged position, releasable means to hold the blocking device in disengaged position, and means to release the last named means.

55 3. A device of the class described comprising a cylinder element, a cross head opera-

tively associated therewith, a support, an element movably mounted thereon including members movable into the path of the cross head, and means to operate said movable element.

70 4. A device of the class described comprising a cylinder element, a cross head operatively associated therewith, a support, a movable element thereon including blocking means movable into the path of the cross head, yieldable means engaged with and tending to move the movable element into blocking position, a detent normally engaged therewith to hold the movable element in inoperative position, detent releasing means cooperative with the cross head to move the detent out of engagement when said releasing means is in a predetermined relation to the crosshead, means to move the releasing means into such relation, and means to hold it out of such relation.

75 5. A device of the class described comprising a cross head guide and supporting framing, a crosshead reciprocable therein, a blocking device movable into the path of the crosshead including longitudinally spaced elements, a cushioning device therebetween, and means to operate the blocking device.

80 6. A device of the class described comprising a cross head guide and supporting framing, a cross head reciprocable therein, a longitudinally movable support on the guide, a blocking device carried thereby movable into the path of the crosshead including longitudinally spaced elements, a cushioning device therebetween, and means to operate the blocking device.

85 7. A device of the character described comprising a cross head guide and supporting framing, a cross head reciprocable therein, a longitudinally movable support on the guide, a blocking device carried thereby movable into the path of the cross head including longitudinally spaced elements, a cushioning device therebetween, yieldable means engaged with and tending to move the blocking device into blocking position,

90 a detent normally engaged therewith to hold the blocking device in inoperative position, detent releasing means cooperative with the cross head in certain positions of the releasing means to move the detent out of engagement, means to move the releasing means into one of said certain positions, means to hold it out of such positions, and a check device to hold said longitudinally movable support at a predetermined limit of its movement, cooperative with the said detent releasing means to release the longitudinally movable support.

100 8. A device of the class described comprising a cross head guide, and supporting framing, a crosshead reciprocable therein, a movable support reciprocable on the guide, a laterally reciprocable frame piece carried by

70

75

the movable support, including an inwardly projected part arranged to engage across the path of the cross head when the frame piece is at the inner limit of its movement, 5 at least one horizontal shaft carried by the inwardly projected part, longitudinally reciprocable members thereon on opposite sides of the frame piece and outwardly of the ends of the shaft, means to limit their outward movement on the shaft, resilient means active thereon to bear them outwardly, and means to operate the frame piece for the purposes described.

9. A device of the class described comprising a crosshead guide and supporting means including an end piece across one end, 15 a cross head reciprocable in the guide, a mov-

able support reciprocable on the guide, means to hold the movable support in initial position at times, a blocking device engageable with the crosshead at times, means tending to operate the blocking device cooperative with the crosshead when in a predetermined relation thereto and means on the supporting means to control the operating means. 20 25

10. A device of the class described comprising a cross head guide, a cross head reciprocable thereon, a support, a movable member on the support engageable in the path of the cross head at times, and means to operate the movable member including cab-controlled devices. 30

In testimony whereof I affix my signature.
JOHN C. MENDONCA.
